DRIVING CONNECTION

1,242,577.

Specification of Letters Patent.

Patented Oct. 9, 1917.

Application filed June 28, 1915. Serial No. 35,765.

To all whom it may concern:

Be it known that we, GEORGE G. MILNE, a citizen of the United States, and a resident of Rye, Westchester county, New York, and
6 WILLARD F. RICHARDS, a citizen of the United States, and a resident of Buffalo, county of Erie, State of New York, have invented certain new and useful Improvements in Driving Connections, of which the
10 following is a specification.

The invention relates to improvements in driving connections, and is especially applicable to the driving of dynamo electric machines from car axles, although it may
15 be found useful in other situations. The object of the invention is to improve upon the driving connection shown in U. S. application for Letters Patent Serial No. 814,055, filed January 24, 1914.

20 More specific objects, features and advantages will clearly appear from the detailed description given below, taken in connection with the accompanying sheet of drawings which forms a part of this specification.

25 In the drawings, Figure 1 illustrates a dynamo driven from a car axle with the improvements in one form applied thereto;

Fig. 2 is a plan view of the driving connection, certain parts being broken away or
30 shown in section to more clearly illustrate certain features;

Fig. 3 is a vertical section through the driving connection, taken on the line 2—2 of Fig. 2 and the line 3—3 of Fig. 4; and
35 Fig. 4 is a section taken on the line 4—4 of Fig. 3 and the line 5—5 of Fig. 2.

Referring to Fig. 1, 1 represents a car body to which is securely attached a dynamo 2. Part of one of the car trucks is
40 shown at 3 provided with car wheels 4 and an axle 5. Contained in a casing 6 is any suitable gearing for driving a shaft 7, the outer end of the casing being supported from a cross bar 8 of the truck by means of
45 a flexible connection 9. A shaft 10 is connected at one end to the shaft 7 by means of a universal joint 11 and at its other to the shaft 12 by means of a universal joint 13. The shaft 12 is journaled in a frame 14
50 rigid with the dynamo 2. The dynamo shaft is shown at 15 and has rigidly secured on its end a disk 16.

Referring more particularly to Figs. 2, 3 and 4, the driving shaft 12 has secured

thereto by a key 17 and nuts 18 and 19, a 55 driving member 20 comprising a recessed casing member having a central stud 21 bored to accommodate the end of the shaft 12. The casing is formed with an integral outer flange 22 to the edge of which are 60 bolted two pairs of semi-circular plates 23 and 24, respectively, by means of bolts 25. Each pair forms a circular disk plate divided in two pieces as indicated with respect to plates 23 at 26 (Fig. 2), the division points of plates 24 being placed 90° from the division points of the plates 23 so that the dividing line of plates 24 does not show. The plates 23 and 24 are cut away at the center to accommodate the driven 70 member 27 which is journaled upon the stud and provided with a circular flange 28 which is bolted to the disk 16 so that it will drive the dynamo. The member 27 and disk 16 are dished to accommodate the end of the 75 shaft 12 and nuts 18 and 19. The driven member 27 is provided with a flange 29 located on the inside of the plates 23 so that the member 27 is prevented from slipping off of the stud 21 after the plates 23 and 24 are bolted in place. A spring 30 is coiled about the axis of the stud 21 and shaft 12, and about the member 27 inside the flange 29. One end of the spring 30 is connected to the member 27 by a pin 31 located in a 85 recess in the member 27. A flange piece 32 is secured to the inner end of member 27 by means of pins 33 so that the convolutions of the spring 30 are held in place on the member 27 between the flange piece 32 and 90 flange 29. Extending about and concentric with the member 27 and shaft 12 is a circular member 34 to which the outer end of the spring 30 is connected by means of a pin 35 situated in a recess therein as shown in Fig. 95 4. The member 34 is recessed along the center of its periphery and provided with apertures 36 therethrough, the device being filled with heavy grease and the apertures 36 permitting of flow from one part to 100 another.

If the parts were left as so far described revolution of the shaft 12 would rotate the casing of member 20 together with the plates 23 and 24 secured thereto, and the members 105 34 and 27 would not be driven. To connect the parts so that member 27 will be driven, the circular member 34 is provided with

holes 37 and the side of the casing 20 and the plates 23 and 24 are provided with a hole 38 and a pin 39 is passed through one of the holes 37 and the hole 38 so that the member 34 becomes locked to the casing and thereby forms a part of the driving member which, upon being rotated by the shaft 12, drives the driven member 27 through the resilient connecting means or spring 30, one end of which spring is connected to the driving member by pin 35 and the other end to the driven member by pin 31. If it is desired the member 27 may act as the driving member and the member 20 as the driven member driving the shaft 12. The spring 30 cushions sudden quick turns given the shaft and prevents their being communicated to the dynamo 2, as would occur in the coupling of cars and the sudden forceful application of the brakes.

The pin 39 is constructed of a suitable size and material to be sheared off by the members 20 and 34 in case the dynamo for any reason should become stopped, as by reason of a hot box therein or for any other reason. Under such circumstances, if the pin 39 or some part were not adapted to give way, it would likely cause breaking of the shafting 7, 10, 12 or other parts which might then drop to the tracks and cause an accident or serious damage. The pin 39 which is thus adapted to give way under such conditions by being sheared off, is held in place by a head 40 and a cotter pin 41 at the other end. 35 When the pin 39 is sheared off the driving member 20 may continue to revolve, being driven by the axle, while the members 27 and 34 will remain stationary and no torque will be exerted on the dynamo shaft 15. 40 When the trouble causing stoppage of the dynamo is remedied, it is only necessary to insert a new pin 39 to put the parts into complete operative condition. By removing the bolts 25, the cap plates 23 and 24 may be removed and all the parts quickly separated for inspection, repair or renewal. By arranging the member 20 with the flange 22 and providing the cap plates 23 and 24, the same act as a casing covering up various parts and keeping dirt and grit therefrom. The pin 39 may be easily removed to permit the generator to be run as a motor for testing.

Although the improvements have been described in great detail with respect to one embodiment of the invention, the invention in its broader aspects is not limited to such details, since many changes and modifications may be made and the invention applied to other situations.

The invention, having been fully and clearly described, what is claimed as new and desired to be secured by Letters Patent, is:—

65 1. A driving connection comprising a ro-

tary driving member and a rotary driven member in axial alignment, a spring coiled about the axis of said members having one end secured to one member and the other end normally operatively connected to the other member, through a member adapted to be broken and permit the driving member to rotate independently of the driven member to prevent breakage of other parts in case the driven member is stopped for any reason while the driving member is rotating.

2. A driving connection comprising a rotary driving member and a rotary driven member, resilient means normally operatively connecting said members whereby the driven member is driven by the driving member through a pin adapted to be sheared to permit the driving member to rotate independently of the driven member to prevent breakage of other parts in case the driven member is stopped for any reason while the driving member is rotating.

3. A driving connection comprising a driving member and a driven member, one of said members comprising two parts, means connecting said parts and adapted to be broken to prevent breakage of other parts in case the driven member is stopped for any reason while the driving member is rotating and resilient means connected to one of said members and to that part of the other member which is actuated by said connecting means, whereby the driving member actuates the driven member through said resilient means and said means connecting said parts.

4. A driving connection comprising a driving member and a driven member, one of said members comprising two parts, a pin connecting said parts and adapted to be sheared thereby to prevent breakage of other parts in case the driven member is stopped for any reason while the driving member is rotating, and a spring connected to one of said members and to that part of the other member which is actuated through said pin, whereby the driving member actuates the driven member through said spring and said pin.

5. A driving connection comprising a rotary driving member and a rotary driven member coaxially arranged, one of said members comprising a rotatable casing having a central stud upon which the other member is rotatably mounted, a circular part connected to said casing member, resilient means connecting said part with said other member whereby the driving member drives the driven member, and means for connecting said part with the casing, said means being adapted to give way to prevent breakage of other parts in case the driven member is stopped for any reason.

6. A driving connection comprising a rotary driving member and a rotary driven

member coaxially arranged, one of said members comprising a rotatable casing having a central stud upon which the other member is rotatably mounted in said casing, a circular part arranged about said other member, means connecting said part with said other member whereby the driving member drives the driven member, and means for connecting said part with the casing, said means being adapted to give way to prevent breakage of other parts in case the driven member is stopped for any reason.

7. A driving connection comprising a rotary driving member and a rotary driven member coaxially arranged, one of said members comprising a rotatable casing having a central stud upon which the other member is rotatably mounted in said casing, a circular part arranged about said other member, a spring connecting said part with said other member whereby the driving member drives the driven member, and means for connecting said part with the casing, said means being adapted to give way to prevent breakage of other parts in case the driven member is stopped for any reason.

8. A driving connection comprising a rotary driving member and a rotary driven member coaxially arranged, one of said members comprising a rotatable casing having a central stud upon which the other member is rotatably mounted in said casing, a circular part connected to said casing member and arranged therein about said other member, resilient means connecting said part with said other member whereby the driving member drives the driven member, and a pin connecting said part with said casing and adapted to be sheared to prevent breakage of other parts in case the driven member is stopped for any reason.

9. A driving connection comprising a recessed disk-shaped casing having a central stud adapted to be secured to a shaft, a member rotatable upon said stud, a circular member situated between said last mentioned member and the outside of said casing, said stud and said members being coaxially arranged, means for connecting said members, and a pin connecting said circular member with said casing and adapted to be sheared to prevent breakage of other parts in case

the driven member is stopped for any reason.

10. A driving connection comprising a recessed disk-shaped casing having a central stud adapted to be secured to a shaft, a member rotatable upon said stud, a circular member situated between said last mentioned member and the outside of said casing, said stud and said members being coaxially arranged, a spring coiled about the axis of said members having one end secured to said circular member and the other end secured to said other member, and a pin connecting said circular member with said casing and adapted to be sheared to prevent breakage of other parts in case the driven member is stopped for any reason.

11. A driving connection comprising a driving member and a driven member, a spring connecting the said members, whereby the driving member drives the driven member, one of said members comprising two parts and a pin connecting said parts adapted to be sheared thereby to prevent breakage of other parts in case the driven member is stopped for any reason, one of said members having a plurality of apertures for said pin whereby the pin may connect the two members in various relative positions of adjustment.

12. A driving connection comprising a recessed disk-shaped casing having a central stud adapted to be secured to a shaft, a member rotatable upon said stud, a circular member situated between said last mentioned member and the outside of said casing, said stud and said members being coaxially arranged, a spring coiled about the axis of said members having one end secured to said circular member and the other end secured to said other member, and a pin connecting said circular member with said casing and adapted to be sheared to prevent breakage of other parts in case the driven member is stopped for any reason, one of said members having a plurality of apertures for said pin whereby the pin may connect the two members in various relative positions of adjustment.

In testimony whereof, we have signed our names to this specification.

GEORGE G. MILNE.
WILLARD F. RICHARDS.
